(57) CLAIM

The ornamental design for a tie for reusable concrete forms, as shown.

DESCRIPTION

FIG. 1 is a perspective view of the tie showing my new design;

FIG. 2 is an end elevational view taken from the left end of the tie shown in FIG. 1, the right end elevational view being a mirror image thereof;

FIG. 3 is a front elevational view thereof, the rear elevational view being a mirror image thereof; and,

FIG. 4 is a top plan view thereof, the bottom plan view being a mirror image thereof.
